TEXTILE FABRIC OR SIMILAR ARTICLE

Filed Sept. 24, 1932

INVENTOR

WILLIAM WILLHEIM.
BY *Edwin Leisohn*

ATTORNEY

UNITED STATES PATENT OFFICE

WILLIAM WILLHEIM, OF NEW YORK, N. Y.

DESIGN FOR A TEXTILE FABRIC OR SIMILAR ARTICLE

Application filed September 24, 1932. Serial No. 45,021. Term of patent 3½ years.

To all whom it may concern:

Be it known that I, WILLIAM WILLHEIM, a citizen of the United States of America, residing at 115 Central Park West, in the city of New York, county of New York, and State of New York, have invented a new, original, and ornamental Design for a Textile Fabric or Similar Article, of which the following is a specification, reference being had to the accompanying drawing, forming a part thereof.

The figure is a plan view of a textile fabric showing my new design. For convenience of illustration and to show the design more in detail the same has been divided. The design is continuous from the selvage AB to the

selvage EF. The dot and dash lines CD and C'D' respectively coincide and over-lie each other. The dot and dash lines ACC'E and BDD'F on the drawing outline the design unit, which unit is repeated in regular succession, as indicated by the extensions beyond the unit boundaries. The drawing is lined to indicate shading.

I claim:

The ornamental design for a textile fabric or similar article as shown and described.

In testimony whereof I have signed this specification.

WILLIAM WILLHEIM.
